UNITED STATES PATENT OFFICE.

DONALD McDERMID, OF IRVINGTON, NEW JERSEY.

ELECTROPLATING-GENERATOR.

1,164,734.

Specification of Letters Patent. Patented Dec. 21, 1915.

Application filed July 22, 1914. Serial No. 852,339.

To all whom it may concern:

Be it known that I, DONALD McDERMID, a citizen of the United States, and resident of Irvington, in the county of Essex and 5 State of New Jersey, have invented a new and useful Improvement in Electroplating-Generators, of which the following is a specification.

The object of my invention is to provide 10 double commutator electroplating generators with devices to conveniently permit the generators to be arranged for either delivering the total output at approximately 6 volts or to deliver the total output at approximately 12 volts, or to divide the output 15 so that it may be delivered in part at 6 volts and in part at 12 volts.

Another object of the invention is to accomplish the foregoing results efficiently in 20 an improved manner and to eliminate the difficulty usually experienced in manipulating the heavy cables which are used as armature leads in this type of generator; and also to make it possible for electroplating generators 25 to be manufactured and placed in stock, ready for sale, either to fill a demand for 6 volt or 12 volt machines.

Another object of the invention is to utilize copper arc shaped bars in place of part 30 of the heavy armature lead cables, which would otherwise have to be bent around inside of the frame of the generators, which cables are objectionable because such cables are so stiff and heavy that they cannot be 35 conveniently manipulated or bent at suitable angles for this purpose; in my invention I make all the armature lead cables the same length and interchangeable.

In double commutator electroplating generators 40 it has been customary to take the leads from the armature to two sets of terminals, one mounted on front and one on the back of the machine, in order that the stiff and heavy cables forming the armature leads 45 may be made as short as possible, and the arrangement of the parts which I have invented saves copper and therefore saves expense, and at the same time increases the convenience of the generator.

50 The invention consists of the improved arrangement and form of the armature leads, the arc bars, and the transfer panel, as will be fully pointed out in the claim.

Referring to the accompanying drawings: 55 Figure 1 is a plan view of my generator

showing the heavy armature leads and the transfer panel mounted on the frame of the generator. Some of the parts are in cross section. Fig. 2 is an elevation of Fig. 1 showing the armature leads connected in parallel at the transfer panel for delivering the total output of the machine at 6 volts. Fig. 3 is a side view of one of the arc bars and shows its relation to the other parts. Fig. 4 is an elevation of the transfer panel and 60 the armature leads connected on to the transfer panel to deliver both 6 and 12 volts. Fig. 5 is like Fig. 4 except that the neutral terminal lug is left off so that the total output of the machine will be delivered at 12 65 volts. 70

Referring particularly to Figs. 1 and 2, an ordinary bipolar, double wound armature, double commutator, electroplating generator is shown, provided at one end 75 with a brush holder stud 10, connected to an arc bar 11, which is also supported by another brush holder stud 12, through the medium of an insulating bushing 13, which also supports the brush holder stud 12 in 80 position in the usual manner. The arc bar 11 also provides a terminal boss 14 into which is inserted a heavy cable armature lead 15, which has a terminal 16. The brush holder stud 12 is attached to a terminal 17 85 which is attached to a lead 18, having another terminal 19. The leads 15 and 18 are similar to each other and have a difference of potential of 6 volts. At the other end 90 of the generator a brush holder stud 20 carries an arc bar 21, which is also supported by another brush holder stud 22, through the medium of an insulating bushing 23, which also supports the brush holder stud 22 in 95 position in the usual manner. The arc bar 21 also provides a terminal boss 24 into which is inserted a heavy cable armature lead 25, which has a terminal 26. The brush holder stud 22 is attached to a terminal 27, which is attached to a lead 28, having another terminal 29. The leads 25 and 28 are similar 100 to each other and have a difference of potential of 6 volts; these leads are also similar to the leads 15 and 18. The leads 15 and 25 are of similar polarity and are connected through their respective terminals 16 and 26 to the connecting bar 30, which is provided with a terminal 31, from which a cable 105 may carry current to a plating tank. The connecting bar 30 is mounted on a transfer 110

panel 32, which is made of insulating material, and secured to the front of the generator. The leads 18 and 28 are of similar polarity and are connected through their respective terminals 19 and 29 to the connecting bar 33, which is provided with a terminal 34 from which a cable may carry current to the plating tank. In the parallel arrangement of the leads shown in Figs. 1 and 2, the generator delivers its total output from the transfer panel to the plating tank at 6 volts.

In Fig. 4 the connecting bar 33 has been removed and the leads 25 and 28 crossed at the transfer panel 32, so that there is a potential of 6 volts between the terminal 31 and a terminal 35 which is shown connected to the terminal 19 through a short connecting bar 36. There is also a potential of 6 volts between the terminal 31 and a terminal 37, which is connected to the terminal 26 by a short connecting bar 38. Thus one plating tank can be operated at 6 volts by connecting it to the terminals 31 and 35. A second tank can be operated at 6 volts by connecting it to the terminals 31 and 37. A third tank can be operated at 12 volts by connecting it to the terminals 35 and 37; in this third tank the full potential of the double armature in series is utilized.

In Fig. 5 the terminal 31 is left off so the generator acts as a straight 12 volt generator, the connections are otherwise the same as in Fig. 4.

In Fig. 3 the shape of the arc bar 11 is shown to illustrate the convenient practical manner in which it allows all the leads to be made short, similar to each other, and to

all be brought to the transfer panel 32 on the front of the generator.

The improved arc bar, the heavy leads of uniform length all on the front of the generator, and the transfer panel make my generator interchangeable for 6 or 12 volts, and while I have described my improvements with relation to a specific electroplating generator, my improvements may be adapted to other types of electroplating and low voltage generators without departing from the spirit of this invention.

I claim:

In the generator for heavy currents of low voltage the combination of a revoluble shaft, an armature and commutator bars carried by said shaft, a brush holder stud of one sign located upon one side of said shaft, a brush holder stud of a different sign located upon the side of said shaft diametrically opposite the first-mentioned stud, an arc bar connected to the first-mentioned stud and in direct conductive connection therewith, said arc bar curving in the proximate form of a semi-circle around said shaft and provided with a hole through which said second mentioned stud extends, a sleeve of insulating material encircling said second mentioned stud and extending through said hole, a conductor connected to said second mentioned stud, and a second conductor connected to said arc bar at a point in close proximity to said second mentioned stud.

DONALD McDERMID.
